RATCHET WRENCH

Emmett Junior Gantz, Burlington, Iowa

Application July 2, 1948, Serial No. 36,707

1 Claim. (Cl. 192—43.1)

1

This invention relates to improvements in ratchet wrenches and particularly to heavy duty ratchet wrenches for loosening or tightening resistant nuts, such as those on the wheel bolts of trucks and busses, where excessive torque must frequently be applied.

It is among the objects of the invention to provide an improved ratchet wrench having a straight shaft capable of withstanding excessive torque having a socket receiving ratchet mechanism at one end and the opposite end shaped to receive a handle or lever extending substantially perpendicular to the shaft, wherein the ratchet mechanism includes a ratchet gear rotatable relative to the shaft, two pair of ratchet dogs pivotally mounted on the end of the shaft and so disposed that the two pair are at diametrically opposite sides of said ratchet gear and the two dogs of each pair are alternatively engageable with the ratchet gear to lock the gear and shaft against relative movement in opposite directions, whereby at least two of the dogs are at all times in engagement with the ratchet gear to divide between them the torque forces applied between the shaft and the ratchet gear, and wherein the ratchet dogs are backed up by shaft-carried abutments which relieve the pressure on the pivot pins pivotally connecting the dogs to the corresponding end of the shaft, and which ratchet mechanism further includes an annular adjusting collar conveniently mounted on the end of the shaft for limited manual rotation between three operative positions for alternatively engaging the dogs with the ratchet gear to lock the shaft and ratchet gear against relative rotation in opposite directions or for engaging all of the dogs with the ratchet gear simultaneously to lock the shaft and ratchet gear against relative rotation in either direction.

A further object resides in the provision of an improved handle and extension lever for a ratchet wrench having a rotatable shaft wherein the handle has at its outer end a pivotally mounted sleeve which may be alternatively positioned for use as a crank handle or grip or as an extension providing increased leverage for the handle, and wherein the extension lever is engageable with the sleeve to further increase the leverage applicable to the wrench.

A still further object resides in the provision of an improved ratchet wrench including a wrench operating handle and extension lever, which is of heavy duty construction and strong and durable in use, economical to manufacture, and particularly convenient to use.

2

The invention will be best understood from a consideration of the following detailed description in connection with the accompanying drawings, nevertheless, it is to be understood that the invention is not confined to the description but is susceptible of such changes and modifications as shall define no material departure from the salient features of the invention as expressed in the appended claim.

10 Figure 1 is a side view in elevation of my wrench.

Figure 2 is a vertical section taken along the line 2—2 of Figure 1.

15 Figure 3 is a horizontal section taken along the line 3—3 of Figure 2.

Figure 4 is a bottom plan view of the body of the wrench with the adjustment collar and cap removed.

20 Figure 5 is an enlarged longitudinal vertical section of the handle for operating the wrench and showing a removable extension for increasing the leverage.

Figure 6 is a transverse vertical section taken along the line 6—6 of Figure 5, and

25 Figure 7 is an enlarged fragmentary side view of the joint for decreasing the length of the operating handle.

Referring more particularly to the drawings, 30 10 designates an elongated wrench shaft, having at one end a tapered enlargement 11 merging into a shank 12. A knurled sleeve 13 is rotatable on the shank and is adapted to be grasped by a hand of the operator during the actuation of the wrench. The shaft has in the enlargement 11, a concentric bore or recess 14 opening to the outer end of the enlargement, a counterbore 15 near its open end and a second counterbore or annular chamber 16 (Figure 4), of greater diameter than the first counterbore, thereby providing a marginal flange or annular wall 17.

An arbor 20 is journaled in the bore 14 and projects through the cylindrical chambers 15 and 16 out of the end of the shaft enlargement and terminates in a plug or stub 21 adapted to be received by a socket piece 22. A ratchet gear 23 is formed integrally on the arbor and is disposed centrally of the chambers 15 and 16. Said arbor is enlarged at 24 outwardly of the ratchet.

As shown in Figure 4, the annular wall 17 is 50 provided with four pockets 25 and 26. A dog 27 is pivoted at 28 in each pocket 25, while a dog 29 is pivoted at 30 in each pocket 26, the portions of annular wall 17 between adjacent pockets 26 overlying the pivoted ends of the dogs and serving as abutments to relieve the pivot pins of any

excessive pressure applied to the dogs in the use of the wrench. Coil springs 31 tend to press the dogs into the teeth of the ratchet 23. The inner face of each dog has transverse ribs 32 for a purpose which will be explained presently.

A collar 35 is rotatably mounted on the outer face of the wall 17 and is manually rotatable to a limited extent in opposite directions on said wall. The outer face of the collar is knurled so that it may be actuated manually. The outer end of the collar is closed by an end wall 36 having a central opening 37 receiving the enlarged portion 24 of the arbor 20. Said end wall also has four arcuately shaped slots 40. A pair of diametrically disposed arcuately shaped lugs 41 project inwardly from the end wall 36, and are received between the two dogs of each pair 27 and 29. The outer curved face of each lug has ribs 42 adapted to engage the ribbed portions 32 of the dogs, as shown in Figure 4, to prevent accidental disengagement of the lugs and the dogs.

An end plate 45 has a plurality of apertured bosses 46 projecting inwardly therefrom and into the arcuate slots 40 in the end wall 36 of the collar 35. The apertures in the bosses extend through the end plate and are aligned with threaded wells 47 in the wall 17 of the shaft enlargement to receive screws 48 for securing the end plate to the body 16 and for retaining the collar 35 and the ratchet gear 23 in place.

The operation of my wrench just described is as follows: The collar 35 when revolved in one direction, as shown in Figure 4, will cause the lugs 41 to engage the dogs or paws 29 and move them to an inoperative position against the tension of the springs 31 so that the ratchet 23, together with the shaft 20 will be locked temporarily to the body 16 by the dogs 27 for turning the socket 22 in the direction indicated by the arrow in Figure 4 for screwing a nut up tight. When the collar 35 is rotated in the opposite direction, the lugs 41 will release the dogs 29 and move the dogs 27 to an inoperative position for unscrewing a nut or bolt by the socket 22. The interlocking ribs or teeth 32 on the dogs and the ribs or teeth 42 on the lugs 41 will prevent the lugs and dogs from becoming separated when the lugs have been positioned by the collar 35.

The shank 12 is operated by a handle 45 which includes a rod 46, a socket 47, adapted to receive a square end 48 on the shank, and an adjustable hand grip 49. The hand grip may be placed at right angles to the rod 46 (Figure 1) or said grip may be rocked until it is aligned longitudinally with the rod (Figure 5) for greater leverage.

The rod 48 has an enlargement 50 at the inner end thereof and said enlargement is bifurcated to receive a flattened end 51 of a rod 52 of the hand grip 49. The enlargement has a cut-out portion 53 to receive a tongue 54 on the flattened portion 51 for retaining the rod 52 aligned with the rod 46. A spring-pressed detent 55 seated in a socket 56 in the enlargement 50 is adapted to engage a notch 57 in said enlargement for maintaining the rods 46 and 52 longitudinally aligned, or to engage a notch 58 for retaining the rod 52 at right angles to the rod 46. A sleeve 60 is received by the rod 52 and is held in place by the head 61 of a bolt 62 threaded into an axial passage in the outer end of the rod 52. The sleeve rotates on the rod 52 to protect the hand of the operator. A bolt 64 provides a pivot for the flattened end 51 of the rod 52.

An extension may be applied to the sleeve and

includes a solid rod 65 having an axial socket 66 for the reception of the sleeve 60 which has diametrically disposed lugs 67 entering notches 68 at the free end of the cylindrical wall of the socket 66. A connecting sleeve 70 has an inturned annular flange 71 at one end which is provided with diametrically disposed notches 72 through which the lugs 67 pass when the connecting sleeve is slipped onto the sleeve 60. The sleeve 70 has a reduced split section 73 provided with an annular grooved portion 74 engaging over an annular rib 75 on the socket portion 66 of the rod 65.

The detent 55 engages the notch 57 (Figure 5) when the rod 52 is extended longitudinally of the rod 46 and the flange 54 is seated in the cut-out portion 53 on the enlargement 50. The connecting sleeve 70 mounted on the inner end of the rod 65 by the rib 75 and groove 74 combination is slipped on the sleeve 60 until the flange 71 engages the lugs 67. The sleeve 70 is turned until the notches 72 align with the lugs 67 when said sleeve is forced inwardly to clear the lugs and the sleeve is turned to move the notches out of alignment with the lugs so that the lugs and flange will prevent accidental displacement of the extension from the sleeve 60. The extension thus applied will increase the leverage of the handle 45 for removing frozen nuts or bolts.

The bosses 46 on the stationary cap 45 (Figure 3) limit the rotary motion of the collar 35 in opposite directions. When the collar and the integrally formed plate 36 are rotated in one direction, one end of each slot 40 is engaged by the associated boss, while when the collar is moved in the opposite direction, the other end of the slot will be engaged by the associated bosses. The lugs 41, when moved to a neutral position halfway between the dogs 27 and 29, will not act on the dogs and the two pair of dogs will be in engagement with the ratchet 23 and either direction of rotation of the handle 45 (Figure 1) will cause rotation of the shaft 20. However, when only one pair of the dogs are engaged, the rotation of the handle in one direction will either tighten or loosen a nut, while the handle may be returned to its former position by the reverse rotation thereof. At this time, the engaged pair of dogs will ride idly over the ratchet 23.

What I claim:

A ratchet wrench comprising an elongated shaft having on one end a tapered enlargement provided in its outer end with an axial bore and a counterbore at the other end of said bore, an annular marginal wall on the end of said enlargement circumferentially surrounding said counterbore, said wall having angularly spaced apart dog receiving pockets therein, a ratchet gear seated in said counterbore and having an arbor journaled in said bore, a stud projecting from said ratchet gear outwardly of the corresponding end of said shaft, ratchet gear engaging dogs pivotally mounted one in each pocket of said annular wall and arranged in two pair with the two dogs of each pair relatively opposed, the portions of said annular wall between pockets receiving the two dogs of each pair of dogs overlying the pivoted ends of such dogs and serving as abutments for applying pressure to the dogs, a manually rotatable annular collar mounted on said annular wall and having an end wall overlying the enlarged end of said shaft, said end wall having an aperture receiving said stud and spaced apart arcuate slots therein, a pair of arcuately shaped lugs carried by said end wall and disposed one lug between the two dogs of

each pair, an end plate overlying the end wall of said collar and having an aperture receiving said stud, screws extending through the end plate and into the enlarged end of said shaft to secure said end plate and said collar to said shaft, said screws extending through corresponding slots in the end wall of said collar to limit rotational movements of said collar relative to said shaft, and spring means acting between said annular wall and said dogs resiliently urging said dogs into engagement with said ratchet gear, said dogs being alternatively movable out of engagement with said gear by said lugs upon manual rotation of said collar and said lugs and said dogs having mutually engaging ribs thereon to releasably secure said lugs in operative engagement with said dogs against accidental displacement.
